UNITED STATES PATENT OFFICE.

ANDRÉ GUÉRET, OF PARIS, FRANCE.

INTERNAL-COMBUSTION ENGINE.

1,231,522.

Specification of Letters Patent. Patented June 26, 1917.

Application filed December 26, 1913. Serial No. 808,873.

To all whom it may concern:

Be it known that I, ANDRÉ GUÉRET, a citizen of the French Republic, residing in Paris, in France, have invented certain new and useful Improvements in Internal-Combustion Engines, of which the following is a specification.

This invention relates to internal combustion engines, and more particularly to those having a rotary sleeve or sleeves.

The invention comprises a packing ring inserted between the sleeve valve in which a port or ports are made and its sliding face, characterized by a protecting lip on one of the two elements (sleeve or face) surrounding the port or ports and extending to the second of the two elements, while the packing ring is formed so that it can be put in place.

20 The invention further comprises a sleeve valve controlled from the top, and further, in internal combustion engines generally, cylinders which are joined by means of ties, inlet and outlet valves which can be interchanged, a compression relief valve, and finally in a sleeve valve internal combustion engine a supplementary sleeve which in one position causes the engine to work as a compression pump.

30 A construction of the engine will be seen in the accompanying drawings, in which—

Figures 1 and 2 show respectively in vertical section at right angles to the axis of the crank, and in horizontal section, the 35 internal combustion engine,

Fig. 3 shows, like Fig. 1, another internal combustion engine,

Fig. 4 shows in elevation the sleeve with which each of the cylinders of the engine of 40 Figs. 1 and 2 is provided.

Fig. 5 shows the sleeve with the packing part removed.

Figs. 6 and 7 show, respectively in vertical section on the line 6—6 of Fig. 2, and 45 in vertical section on the line 7—7 of Fig. 2, the sleeve, as well as the adjoining parts of the engine.

Figs. 8 and 9 show in the same way respectively as Fig. 4 and Fig. 5, the sleeve with which the engine, or each of the cylinders of the engine of Fig. 3 is or are provided.

Figs. 10—13 show sections of the cylinder and illustrate the sleeves in each of the positions occupied during each of the four strokes thereof.

Fig. 14 shows, in the same way as Figs. 1 and 3, another internal combustion engine according to this invention.

A cylinder *a* is provided with a pair of ports, an admission port *b*, and an exhaust port *c*, in which cylinder a sleeve *d* with a port *e* is arranged so that the said sleeve can turn about its axis. The port *e* is thus brought to coincide successively with one 60 and with the other of the said ports *b* and *c*.

In order to pack the joint between the cylinder or cylinders *a* and the sleeve *d* the sleeve *d* is provided with such a recess that it is on the same level as the port *e* of the 70 same. The said port is provided with a lip *e*¹ which, as soon as the sleeve is in place in the cylinder, projects up to the inner wall of the latter. In the recess is mounted a ring provided with such an opening that it 75 frames the lip *e*¹ so that the lip protects the edges of the opening. This ring is either as shown in Figs. 4—7 constituted by three superposed and joined elementary segments, the first and the third of which are made 80 and cut in the usual manner, and the second cut out to fit between them, of a height equal to or slightly greater than the height of the lip *e*¹, leaving a small clearance between the edges of its opening and the lateral edges of 85 the said lip *e*¹ or, as shown in Figs. 8 and 9, by a single ring cut out as shown in Fig. 8.

These rings are held in place by projections either secured, or made during the making of the said recess, and arranged so 90 that, when the sleeve rotates, they pull on the ring to prevent it from scraping the cylinder. It will be seen that the ends of the ring being protected from any direct action of hot gases, wear out much more 95 slowly, and either no leak is produced during the passage of the gases through the port *e*, or, if there is such a leak the said gases, owing to the expansion which they have to undergo in passing the lip *e*¹, do not 100 press the ring against the cylinder much more heavily than it is already pressed by its own elasticity; and finally, there is no wear either of the ring or of the sleeve carrying it, or of the cylinder itself.

105 The engine has also a compression relief valve *f*, which is mounted so that it is on the same level as the port *e*, and consequently can be brought into communication with the interior of the cylinder through 110 the said port, and also the said port uncovers it a certain time before the correspond-

ing piston arrives at the end of the compression stroke. Owing to this a charge remains in the cylinder at the end of each compression when the compression relief valve is open and it is possible, if the dimensions and the position of the said valve have been properly chosen, to obtain starting by means of the compression charge.

In order that the engine may work, whenever desired as a compression pump, to make it act as a brake, between the cylinder or cylinders and the corresponding sleeve is inserted a supplementary sleeve d^o which is provided with ports b^o and c^o so that when it occupies the normal position, as shown in Fig. 2, the said ports coincide respectively with the admission port b and with the exhaust port c and also the position of the said ports b and c being chosen for the purpose, it is possible to stop completely, by giving a suitable angular movement to the said supplementary sleeve, the coincidence of the ports, as shown in Figs. 10-13. When the angular movement has been produced, there takes place at each down stroke of the piston (in spite of the engine being a four-stroke one), a suction of air, for which reason, the supplementary sleeve and the cylinder are provided respectively with a port e^o and a port a^o such that they coincide when the said angular movement has been made, and that then they enable the piston to draw in air during the stroke corresponding in normal working, to the expansion stroke. Also, the position of the ports b and c is such, that when the coincidence between the ports c^o and a^o takes place, there is also a coincidence between the ports e^o and b . Again, the conduit g for the admission of the explosive mixture is provided with a valve g^o which, when it is as shown in full lines in Fig. 2, does not act, but on the contrary, when it is in the position shown in the Fig. 2 in dotted lines, opens directly to the atmosphere that portion of the conduit which is situated below the valve. Finally, to the valve is connected a device for operating the supplementary sleeve d^o , in such a manner as to obtain simultaneous control of these two parts. Owing to this arrangement and as shown in the corresponding figures, the result desired is attained.

The valves of the engine are symmetrical which is necessary to make the engine reverse and the admission and exhaust conduits are combined, both with each other and with valves for the purpose, so as to enable the respective connections of the said conduits and of the ports at which they terminate, to be reversed, by acting on the said valves. To this end are used, as shown in Fig. 2, two similar conduits g^1 and g^2 terminating respectively at the port b and at the port c of the cylinder or cylinders a

and branched at their origin on two joint branches h^1 and h^2 , which in their turn, are branched at their center, on a conduit g connected to the carburetor, and on a conduit i connected to the atmosphere, and also provided with slide valves j^1 and j^2 adapted to act by means of a rocking lever j and to reverse at will. This rocking lever j , also acts on the system for regulating the advance and the retardation of ignition.

The sleeves are not controlled from below as done hitherto and as shown in Fig. 14, but from the top, as shown in Fig. 1, that is to say, by means of a cover or spider k secured to the upper part of the sleeve or sleeves and a pin l secured to the said spider with a pinion m secured at the top of the said pin. Or the sleeves may be controlled as shown in Fig. 3, by means of an upper extension of the sleeve or sleeves, and of a pinion m secured at the top to the said extension.

The cylinders are connected together by means of long ties such as shown at n in Fig. 2, so that the said cylinders are cast with one and the same pattern which is of advantage when the foregoing arrangements are adopted.

The detailed arrangements of the engine are such as are shown in the drawings and require no further explanation.

The invention is not limited to those features more particularly described, but comprises any modifications within the scope of the claims.

What I claim as my invention and desire to secure by Letters Patent is:—

1. An internal combustion engine comprising a fixed cylindrical element having a port, a rotary cylindrical element provided with a port to register with the port of the fixed cylindrical element, and means for preventing leakage of fluid between said elements embodying a projecting lip surrounding the port in one of said elements through which port the gases from the combustion chamber of the cylinder pass in order to escape between said elements, said lip being adapted to contact with the wall of the other element, and a split ring having its ends cut out to surround the said lip with a certain lateral clearance and having its joint substantially in line with the axis of the port surrounded by said lip.

2. An internal combustion engine comprising a fixed cylindrical element having a port, a rotary cylindrical element provided with a port to register with the port of the fixed cylindrical element, said elements being fitted one within the other and the port of the inner element communicating with the combustion chamber of the cylinder, and means for preventing leakage of fluid between said elements embodying a projecting lip surrounding the port in the inner element and adapted to contact with the wall of

the outer element, and a split ring having its ends cut out to surround the said lip with a certain lateral clearance and having its joint substantially in line with the axis of the 5 port surrounded by said lip, the width of the ring being greater than the width of said port and of the upper and lower portions of the lip, each end of the ring being provided with a recess of a width equal to 10 the width of the port and of the upper and lower portions of the lip, and of a depth substantially equal to half of the width of said port and of the lateral portions of the lip.

3. An internal combustion engine comprising a fixed cylindrical element having a port, a rotary cylindrical element containing a 15 combustion chamber and provided with a port to register with the port of the fixed cylindrical element, and means for preventing leakage of fluid between said elements embodying a projecting lip surrounding the port of the rotary element and adapted to contact with the wall of the coöperating fixed element, the rotary element also having 20 a circumferential groove, and an annular packing fitted in said groove and surrounding said lip, the packing having a split portion 25 adjacent to said lip.

4. The combination with relatively rotatable inner and outer cylindrical elements having ports adapted to register, the inner 30

element containing a combustion chamber, and having a circumferential groove in its wall which faces the adjacent wall of the other element and also having a lip projecting from said groove and surrounding the respective port, said lip being adapted to co-operate with the adjacent wall of the coöperating member, and a circular packing contained in said groove and surrounding said 35 lip, the packing having a split portion with the ends thereof adjacent to said lip. 40

5. In an internal combustion engine, the combination of a cylinder, a piston reciprocable therein, a compression relief cock 45 adapted to communicate with the combustion chamber of the cylinder, and a valve having an intake and exhaust controlling port, the port of said valve also controlling communication between the combustion chamber of 50 the cylinder and the compression relief cock, said valve operating to cut off communication between the combustion chamber of the cylinder and the relief cock during the compression stroke of the piston. 55

In testimony whereof I have hereunto set my hand in presence of two subscribing witnesses.

ANDRÉ GUÉRET.
